UNITED STATES PATENT OFFICE.

LOUIE E. WHITCOMB, OF CHICAGO, ILLINOIS, ASSIGNOR TO INTERNATIONAL HARVESTER COMPANY, A CORPORATION OF NEW JERSEY.

SPINNING AND BALLING MACHINE.

1,427,667.

Specification of Letters Patent. Patented Aug. 29, 1922.

Application filed November 26, 1920. Serial No. 426,400.

To all whom it may concern:

Be it known that I, LOUIE E. WHITCOMB, a citizen of the United States, residing at Chicago, in the county of Cook and State of Illinois, have invented certain new and useful Improvements in Spinning and Balling Machines, of which the following is a full, clear, and exact specification.

This invention relates to mechanism for 10 winding threads, cord, twine, etc., into a cylindrical cop or ball in what is known as the universal winding and has special relation to a combination of such a machine with the spinning mechanism for forming the 15 twine.

In the manufacture of binder twine, for instance, it has heretofore been necessary, in order to obtain a cop of uniform winding and maximum density, to first wind the 20 twine on bobbins by special machinery and later deliver the twine from these bobbins to winding mechanism, and the object of this invention is to provide a form of winding mechanism that will receive the twine direct 25 from the spinning mechanism and operate in conjunction therewith to make and wind the twine as one operation while producing a dense and evenly wound cop, thus eliminating the intermediate step of winding on bobbins with resulting economy in time and 30 labor, and reduction in the amount of machinery required.

This object has been accomplished by providing a machine in which the spinning and 35 winding mechanisms are both driven from a single source of power, in this case an electric motor, and in which the twine which leaves the spinning mechanism at a constant rate is received by the winding mechanism 40 and laid on the cop evenly and at uniform tension, the uniform action of the winding mechanism being obtained by employment of novel compensating means through which the reciprocative speed of the cop being 45 wound is automatically synchronized with its rotative speed.

With the above named and other incidental objects in view, my invention consists of the organization, details of construction, parts, 50 or their equivalents, hereinafter described and more particularly defined in the claims.

Having reference to annexed drawings,— Fig. 1 is a plan view of a machine embodying my invention.

Fig. 2 is a side elevation of the same. Fig. 3 is a vertical longitudinal section on

the line 3—3 of Fig. 1, with part of the motor omitted.

Fig. 4 is a sectional view on the line 4—4 of Fig. 1. 60

Fig. 5 is a sectional view on the line 5—5 of Fig. 2.

In the present embodiment of my invention the mechanism employed consists of a suitable support 10 on which there is mounted the driving element for the machine, in this case an electric motor 11. The armature of this motor is fixed to a hollow shaft 12, on one end of which is secured a flyer 13, which is thus driven by the motor and which 70 in turn drives the spinning mechanism shown at 14, from which the power is transmitted through the shaft 15 to a mechanism for preparing and combing the sliver, which is not shown. Mounted in such manner as to 75 both rotate and reciprocate within the hollow shaft 12 is a hollow spindle shaft 16, which is thus positioned on the axis of the flyer 13, and which extends within the flyer and has on its end the collapsible cop spindle 80 17. At the opposite end of shaft 12 from that to which the flyer is fixed there is secured a driving gear 18 which is in geared relation with a shaft 19 adjacent thereto, which is mounted in suitable bearings on the 85 supporting frame and is sleeved within a hollow shaft 20 to which it is connected by the friction drive or clutch 21. The hollow shaft 20 has fixed thereto a gear 22 which meshes with a larger gear 23, secured to a 90 sleeve 24, which is splined on shaft 16, which may thus reciprocate within the sleeve 24 but must rotate therewith. Sleeve 24 also has secured thereto a second gear 25 which transmits an equal rate of speed to a gear 26 95 fixed on a hollow shaft 27 which is journaled on a shaft 28 and mounted in suitable supports on the frame at the opposite side of shaft 16 from shaft 19. Shaft 28 has fixed thereto gear 29, which meshes with gear 18 100 and is driven direct from the motor. It will be seen from the mechanism so far described that the flyer 13 will be driven direct from the motor at a relatively high rate of speed and that the spindle shaft 16 will also be 105 driven from the motor and rotate in the same direction as the flyer, but at a somewhat reduced rate of speed through shafts 19 and 20 and the interposed friction clutch 21.

In order to give the spindle shaft 16 its reciprocative movement and to properly syn-

chronize this movement with its rotative movement, I provide on shaft 28, which is driven direct from the motor, and on hollow shaft 27, which is driven through sleeve 24, a differential planetary transmission which comprises a sun gear 30 on the end of shaft 28 and a similar sun gear 31 on shaft 27. These mesh with planetary gears mounted on a double carrier 32 which is journaled on shaft 28 and provided with the parallel arms 32^a, on each of which a pair of planetary gears 32^b is journaled. One pair of these planetary gears is in mesh with the sun gear 30 on shaft 28 and also with the teeth of an internal-gear wheel 33 which is fixed against rotation. The other pair of planetary gears which is in mesh with the sun gear 31 on shaft 27 is also in mesh with the teeth of the internal gear wheel 34 which is journaled on shaft 27 and has fixed thereto and rotating therewith the gear wheel 35. The gear wheel 35 meshes with a second gear wheel 36 which is secured to a cam shaft 37 journaled in suitable bearings on the supporting frame and carrying the cam 38 which has a peripheral cam groove 38^a and on the end of the shaft 16 there is secured a clamp 39 which carries a depending pintle 40 which engages the cam groove 38^b. A slotted guide plate 41 is preferably provided to guide the movement of pintle 40.

The mechanism above described constitutes the means by which the flyer and spindle are driven in unison and the cop spindle simultaneously reciprocated within the flyer. The means for receiving and guiding the twine consists of the tension mechanism 42, which is of ordinary construction and receives the twine from the twisting mechanism at 14, stretching and drawing it off and then delivering it to the guide 43 which is pivotally mounted intermediate its ends on one of the bars of the flyer and which comprises the presser finger 43^a provided with the necessary eye and grooves for reception of the twine or thread and with the weighted end 43^b which is provided with an arcuate slot 43^c engaged with a pin on the flyer for limiting the rocking movement of the guide. With this construction the pressure of the guide finger on the cop is regulated by centrifugal force and is practically uniform at all times during formation of the cop, indicated at 44. The cop is held on the collapsible spindle 17 controlled by a rod 46 which extends the length of shaft 16 and has a projecting end 46^a by which the rod is moved longitudinally to collapse and expand the spindle. This particular structure forms no part of my present invention.

The operation of the mechanism above described is substantially as follows: the twine being wound is produced at a constant rate of speed by the spinning mecha-

nism and passes from the tension mechanism 42 to the guide element 43, from which it is delivered in spiral windings to the cop on spindle 16. With the mechanism in action and the cop being started, the flyer 13 and the spindle 16 are both rotated in the same direction at high speed, but owing to the gear relation between the motor and spindle drive, the spindle normally rotates at somewhat slower speed than the flyer and their difference in speed represents the rate at which the twine is wound on the cop. As the cop grows in size the drag of the flyer against the cop and the spindle shaft increases and tends to rotate this shaft at nearer its own speed. When this drag becomes sufficient, slippage occurs in the clutch 21 and the speed of shaft 16 becomes gradually greater than its normal drive speed. As this occurs sleeve 24 and therefore shaft 27 are given increased speed, which is communicated to the differential mechanism, the action of which is such as to decrease the rotative speed of gear 34 and consequently of the cam shaft 37 and of the reciprocative speed of the spindle shaft 16 in proportion as the speed of shaft 27 and sun-gear 31 increases. It therefore follows that as the cop increases in size its rate of reciprocation will decrease just sufficiently to allow the twine to be placed in close and even spirals on the cop and that this action will be wholly automatic.

The mechanism above described exemplifies but one form which my invention may take and it will be evident that other arrangements of the essential elements and substitution of equivalent means are possible within the scope of the appended claims.

I claim as my invention:

1. A balling and spinning machine comprising the combination with spinning mechanism producing twine at a constant speed, of balling mechanism comprising means for tensioning and guiding the twine and means for winding the twine in a cop, including a flyer and spindle driven at differing rotative speeds by driving means connected to both, means permitting increase in the rotative speed of the spindle as the cop is being formed, and means for reciprocating the spindle during rotation, including means governed by change in rotative speed of the spindle for slowing its rate of reciprocation as its rotative speed is increased; said means including a differential transmission having gears driven from the flyer and spindle respectively and connected to the reciprocating means for the spindle by gearing driven at a speed governed by the difference in the respective speeds of said gears.

2. In a spinning and balling machine, a flyer, a longitudinally reciprocable spindle positioned on the axis of said flyer, means for positively rotating said flyer and spin-

- dle in the same direction at different relative speeds and for simultaneously reciprocating the spindle, means for permitting the spindle to rotate at increasing speed as the winding of a cop progresses and means controlled by the increasing speed of the spindle for correspondingly decreasing its reciprocative speed, comprising synchronizing mechanism having separate geared connections between one part of said shaft and the drive element and between the other part of said shaft and the spindle, and a driving connection between said differential mechanism and said spindle reciprocating means, the differential mechanism imparting reduced speed to the reciprocating means when the drive speed from the spindle increases.
- 5 5. A balling and spinning machine comprising the combination with spinning mechanism producing twine at constant speed, of balling mechanism comprising an electric motor, a hollow shaft on which the armature of said motor is secured and having a flyer 55 fixed thereto through which the spinning mechanism is driven, a reciprocable spindle within said flyer on a shaft journaled in said hollow shaft and extending beyond it at either end, a countershaft having two sections connected to permit slippage, a geared connection between said hollow shaft and one section of the countershaft and between the second section of said countershaft and the spindle shaft and adapted to rotate the 60 spindle shaft in the same direction as the flyer at a reduced rate of speed, means for reciprocating the spindle shaft in the hollow shaft, and differential mechanism comprising a gear driven from said hollow shaft, 65 a second gear driven through the spindle shaft and two sets of planetary gears mounted on a common carrier and in mesh with said gears respectively, a fixed gear wheel in mesh with one set of planetary gears, a 70 second gear wheel in mesh with the second set and a geared connection between said second wheel and the reciprocating mechanism.
- 10 3. In a spinning and balling machine, a flyer, a longitudinally reciprocable spindle positioned on the axis of the flyer, a driving element secured to the flyer, a slower driving connection between said driving element and spindle, including a friction clutch, 20 means for reciprocating said spindle and means for driving said reciprocating means comprising differential mechanism geared to said reciprocating means and driven from both the driving element and spindle.
- 15 4. A balling and spinning machine comprising the combination with spinning mechanism producing twine at constant speed, of balling mechanism comprising a driving element, a flyer secured to said driving element and driving the spinning mechanism, a reciprocable spindle positioned on the axis of said driving element and flyer, a countershaft having two parts connected to permit slippage, a geared connection between said 30 drive element and one part of said shaft and between the other part of said shaft and the spindle, the latter normally imparting reduced speed to the spindle, reciprocating means connected to the spindle, a second 35 two-part shaft having its parts connected by differential drive mechanism, a driving con-

In testimony whereof I affix my signature.

LOUIE E. WHITCOMB.
